[57] CLAIM

The ornamental design for integrated circuit carrier, as shown and described.

DESCRIPTION

FIG. 1 is an isometric view of my new design for integrated circuit carrier;

FIG. 2 is a top view of my new design for integrated circuit carrier;

FIG. 3 is a bottom view of my new design for integrated circuit carrier;

FIG. 4 is an end view of my new design for integrated circuit carrier, the opposite end being a mirror image;

FIG. 5 is a side view of my new design for integrated circuit carrier as seen from the left of FIG. 2;

FIG. 6 is a view of the side opposite that shown in FIG. 5.

FIG.1.

FIG.2.

FIG.3.

FIG.4.

FIG.5.

FIG.6.
